US00D740866S

(12) **United States Design Patent**
Herrmann et al.

(10) **Patent No.:** **US D740,866 S**
(45) **Date of Patent:** **** Oct. 13, 2015**

(54) **FACE GEAR**

- (71) Applicant: **Eaton Corporation**, Cleveland, OH (US)
- (72) Inventors: **Paul N. Herrmann**, Clinton Township, MI (US); **Steven J. Cochren**, Commerce, MI (US); **Sandeep Kumar**, Maharashtra, IN (US); **Steven A. Rudko**, Eastpointe, MI (US); **Stephen P. Radzevich**, Sterling Heights, MI (US); **Matthew G. Fox**, Ceresco, MI (US); **Daniel Philip Fisher**, Coldwater, MI (US)
- (73) Assignee: **Eaton Corporation**, Cleveland, OH (US)
- (**) Term: **14 Years**
- (21) Appl. No.: **29/444,099**
- (22) Filed: **Jan. 25, 2013**

Related U.S. Application Data

- (63) Continuation-in-part of application No. 13/737,713, filed on Jan. 9, 2013, which is a continuation-in-part of application No. 12/760,988, filed on Apr. 15, 2010, now Pat. No. 8,353,800, and a continuation-in-part of application No. 12/814,905, filed on Jun. 14, 2010, now abandoned.

(57) **CLAIM**

The ornamental design for a face gear, as shown and described.

DESCRIPTION

FIG. 1 is a front perspective view of a first embodiment of a face gear showing our new design;

FIG. 2 is a rear perspective view thereof;

FIG. 3 is a front plan view thereof;

FIG. 4 is a rear plan view thereof;

FIG. 5 is a right side view thereof, the left side view being a mirror image thereof;

FIG. 6 is a top view thereof, the bottom view being a mirror image thereof; and,

FIG. 7 is an enlarged view of the portion illustrated in circle 7 in FIG. 1.

The broken lines shown in the drawings are included for illustrative purposes only and form no part of the claimed design.

1 Claim, 6 Drawing Sheets
